UNITED STATES PATENT OFFICE

DE WITT C. RUFF, 2D, OF ST. PAUL, MINNESOTA

RADIATOR HANGER

Application filed June 30, 1928. Serial No. 289,380.

It is the object of this invention to provide a novel and inexpensive hanger adapted to facilitate the work of securing radiators upon walls. Further objects are to adapt a hanger for use with all of the radiators of the modern type which vary in width between wide limits, to make it unnecessary to provide hanger brackets or arms of various sizes and to avoid certain other adjustments heretofore required to hang the radiators of different widths.

As is well known, radiators of the type which have recently come into wide use for heating buildings are formed in longitudinally spaced sections of various widths and the heating fluid passes from one section to another through centrally located bosses or nipples connecting the sections. To hang such radiators on a wall it is the present common practice to provide a supporting bracket which engages one of the bosses connecting the sections. As such bosses are located at various distances from the wall, in radiators of different widths, it has heretofore been necessary for a heating contractor to keep on hand a large number of brackets of different sizes or, as is the case with the device of my copending application, Serial No. 235,304, filed November 23, 1927, to provide an extensible bracket arm. By the present invention I further facilitate the operation of hanging radiators and reduce the cost of the apparatus required to meet modern conditions by providing a hanger which can be used with any of the common types of wall radiators because the securing means engage a part of the radiator which is not variously located relative to the wall.

The invention will be best understood by reference to the accompanying drawing in which Figure 1 is a perspective view of the supporting clamp attachment for the radiator; Fig. 2 is a side view of my improved hanger in place upon a wall and illustrating its preferred location relative to a radiator to be supported, the radiator and wall being shown in vertical section; Fig. 3 is a plan view of the radiator support showing the connections with the wall and radiator tubes, a fragmentary portion of the radiator and

wall being shown in horizontal section; Fig. 4 is a typical central, vertical section through the radiator support and showing its relation to the wall and one of the radiator tubes; Fig. 5 is a plan view of the spacing member in place upon a radiator and Fig. 6 is a detail side view of the spacing member with the bolt removed.

My device may be employed to hang a radiator 7 of common type upon a wall 8. As the sections of the radiator 7 vary in width between wide limits, I secure my supporting means to the tubes 9 of the radiator adjacent to the wall 8. A clamp plate 10 is provided with laterally projecting wings 11 adapted to engage the inner surfaces of the tubes 9 adjacent to the wall. Opposite the wings 11 a bar or gripping member 12 is located to engage the outer surfaces of the tubes 9. The bar 12 is connected to the plate 10 by a bolt 13 having a nut 14 threaded upon its inner end and engaging the plate 10. It will thus be evident that the plate 10 with its wings 11 constitutes one gripping member while the bar 12 constitutes the other gripping member of a clamp adapted to be secured to the tubes of a radiator. I prefer to offset the central portions of the plate 10 and bar 12 toward each other so that when the bolt 13 is tightened to grip the tubes 9 the plate and bar are securely held against turning. By this arrangement the bolt 13 is also held against rotation when the nut 14 is tightened from the inner or back side of the radiator, as in making the clamp fast to the radiator.

Projecting upward and obliquely toward the wall from the upper edge of the plate 10 is a bracket 15 formed with a hook-like flange 16 adapted to be hung upon a wall engaging plate 17. This plate 17 is preferably formed from heavy gauge sheet metal and has a central perforation to receive an anchor bolt 18. The plate 17 may be held in place upon the wall 8 by applying a nut 19 to a threaded end of the bolt 18 which projects through the hole in the plate 17. Along its upper edge the plate 17 is formed with an outwardly bent flange 20 and an upturned part 21 of the flange 20 is parallel to the wall. The upper edge of the part 21 is horizontal, while at

each end a stop lug 22 projects upward. Thus the bracket 15 may be hung upon the upper edge of the part 21 and is slideable longitudinally thereon between the limits determined by the stop lugs 22. Near its lower edge the plate 17 is preferably formed with a pair of teeth 23 adapted to be pressed into the surface of the wall 8 to prevent turning of the plate 17 upon the anchor bolt 18 when in use.

A spacing member 24 for retaining the radiator in proper upright position is provided. This member 24, as best shown in Figs. 5 and 6, is formed from a rectangular band of heavy sheet metal which is bent transversely to form a flat side 25 adapted to bear against the wall and a pair of gripping members 26 adapted to be drawn together upon a tube of the radiator by means of a bolt 27. The gripping members 26, as shown in Fig. 6, each have a series of perforations 28 to receive the bolt 27.

Pairs of the perforations 28 are located at various distances from the wall to permit adjustment of the position of the bolt 28. The bolt 27 has a suitable head on one end and a nut 29 threaded upon its opposite end severally engaging the outer surfaces of the clamping members 26. The bolt 28 affords means for clamping the gripping members 26 upon a tube 9 and also constitutes an abutment for the inner periphery of said tube, as shown in Fig. 5.

In the construction of a building preparatory to mounting a radiator upon a wall, one or more of the anchor bolts 18 are secured in the wall at points where they will be required for hanging a radiator. Subsequently a wall plate 17 is secured to an anchor bolt 18 with the supporting edge of the part 21 in horizontal position. After simple measurement of the location of the anchor bolt 18, the clamp, consisting of the plate 10 and bar 12 with the connecting bolt 13, may be properly located upon the back or inner side of the radiator, the height of the clamping bolt 13 from the floor corresponding to the height of the anchor bolt 18. To secure the clamp upon a pair of the tubes 9 the bar 12 is first turned upon the bolt 13 so that it is parallel to the tubes and is then inserted between them. The bar 12 may then be turned so as to span the space between the tubes and engage their surfaces remote from the wall. Now, by tightening the nut 14, the tubes 9 are securely gripped between the wings 11 of the plate 10 and bar 12.

The spacing member 24 may be secured to the radiator (preferably before it is mounted on the wall) by merely tightening the bolt 27 to grip one of the tubes 9 between the gripping members 26. Finally with the bracket 15 and spacing member 24 secured to the tubes 9 it is only necessary to raise the radiator and place the hook-like

flange 16 of the bracket 15 in engagement with the upper edge of the flange part 21. Subsequently, if it becomes necessary or convenient to change the longitudinal position of a radiator (as in making the pipe connections), this may be readily accomplished because the clamp is freely slideable along the supporting flange of the wall engaging plate 17. This feature of the invention also makes it unnecessary to accurately locate the anchor bolts 18 relative to the pipe connections. It is also unnecessary to accurately locate the anchor bolts 18 at any predetermined height from the floor because it will be evident that the clamp plate 10 and bracket 15 may be secured to the radiator at any desired height to compensate for the position of the anchor bolt.

It will now be evident that with my improved hanger a radiator may be suspended from a point above its center of gravity. With such arrangement, in the absence of the spacing member 24, the lower end of the radiator would swing inward and rest against the wall. However, by means of the spacing member 24 the lower portion may be held out at the desired distance from the wall and the bolt 26 constitutes an abutment for the tubes of the radiator adjacent to the wall. Where as is sometimes the case, the surface of the wall is not vertical, or has irregularities such as projections or depressions opposite the spacing member 24, such irregularities may be compensated for by adjusting the position of the bolt 27 in the series of perforations 28. In this manner the radiator may be mounted in proper upright position in all cases. The spacing member 24 is not secured to the wall and may be located in any convenient position upon the lower portion of the radiator. Ordinarily only one spacing member will be required for each radiator irrespective of the number of wall engaging members and suspension units that are required. It will now be understood that my improved radiator hanger greatly facilitates the work of hanging radiators because all adjustments and fastenings may be made before placing the radiator upon its wall support.

Having described my invention what I claim is new and desire to protect by Letters Patent is:

1. In a radiator hanger, a wall engaging member adapted to be secured to a wall, means adapted to engage a radiator above its center of gravity for pivotally suspending the same from said wall engaging member, a separate spacing member having a side adapted to bear freely against the wall beneath said wall engaging member, gripping members integral with said side and projecting outward from the wall, said gripping members being formed with a series of perforations to receive a bolt and a bolt

adapted to be selectively inserted in said perforations to adjust the spacing of the lower part of the radiator from the wall and arranged to draw said members together upon

5 a tube of the radiator adjacent to the wall to secure said gripping member thereto, said bolt constituting an abutment for engagement with said tube.

2. A radiator hanger having in combination means for pivotally suspending a radiator from a wall, a pair of similar, horizontally spaced, arms extending to the wall and connected by a transverse member adjacent to the wall, said arms being arranged for insertion between the tubes of a radiator and to engage the same for holding the radiator in spaced relation to the wall, and an abutment for the wall side of a radiator extending transverse said arms.

20 3. In a radiator hanger means for pivotally suspending a radiator from a wall, a sheet metal spacing member having a pair of arms extending to the wall and a cross member resiliently connecting said arms together at the wall and means for retaining said arms in gripping engagement with a radiator and for affording an abutment for the wall side of the radiator.

4. In a radiator hanger means for pivotally suspending a radiator from a wall, a sheet metal spacing member having a pair of arms, each abutting against the wall at one end and formed to grip a radiator tube at its other end and a bolt connecting said arms together and affording an abutment for the wall side of the radiator.

In testimony whereof, I have hereunto signed my name to this specification.
